PROPELLER SHAPING MACHINE

William G. Dunn, Clarinda, Iowa

Application September 23, 1937, Serial No. 165,364

3 Claims. (Cl. 144—143)

An object of my invention is to provide a machine for shaping propellers, the machine being comparatively simple in construction, yet effective in its operation.

5 A further object is to provide a machine in which a pair of propeller blanks may be clamped, and having a mandrel for shaping the front of one of the blanks and the back of the other, the propeller blanks being mounted on a carriage, means being provided for moving the carriage and thus feeding the blanks along the shaping knives.

10 A further object is to provide means for separating the shaping knives from the blank adjacent to the hub of the blank, whereupon the carriage may be returned and the blanks adjusted for another shaping operation thereon.

15 A further object is to provide a mandrel having two sets of knives, one for shaping the comparatively flat front of the propeller blade, and the other for shaping the back of the blade with an air-foil contour, the line of travel of the blank lying in lengthwise inclined position on the carriage, as it passes under the knives being such as 20 to taper the blade in thickness from tip to hub of the blank.

25 A further object is to provide mechanism which is partially automatic for advancing the carriage and stopping it when the blade has been shaped to the hub portion of the blank.

With these and other objects in view, my invention consists in the construction, arrangement and combination of the various parts of my propeller shaping machine, whereby the objects contemplated are attained, as hereinafter more fully set forth, pointed out in my claims, and illustrated in the accompanying drawings, in which:

Figure 1 is a plan view of a propeller shaping machine embodying my invention.

40 Figure 2 is a front elevation of same, parts thereof being broken away and other parts being shown in section to illustrate details of construction.

45 Fig. 3 is a diagrammatical view of a blank after the first shaping operation has been performed thereon.

Figure 4 is a similar diagrammatical view of the blank after the second shaping operation has been performed thereon.

50 Figures 5 and 6 are diagrammatical views of the blank after the third and fourth shaping operations have been performed thereon, Figure 6 illustrating the completed blade.

55 Figures 7, 8, 9, 10 and 11 are sectional views on the lines 7—7, 8—8, 9—9, 10—10 and 11—11 respectively of Figure 3.

Figures 12, 13, 14, 15 and 16 are sectional views on the lines 12—12, 13—13, 14—14, 15—15 and 16—16 respectively of Figure 5.

60 Figures 17, 18, 19, 20 and 21 are views corre-

sponding to Figures 12, 13, 14, 15 and 16 respectively showing the formation of a propeller in a modified type of my machine designed for producing a progressive change in pitch of the blade from tip to hub of the blank, or to provide a blade with helical pitch.

Figure 22 is a vertical sectional view of a modified form of machine, taken on the line 22—22 of Figure 24.

Figure 23 is a sectional view on the line 23—23 of Figure 22.

Figure 24 is a plan view of the modified form of machine.

Figure 25 is a vertical elevational view partly in section taken on the line 25—25 of Figure 24.

On the accompanying drawings I have used the reference character F to indicate generally a frame, C a carriage and M a mandrel.

The frame F may be suitably supported such as by legs 24 resting on a floor surface or the like 25. The mandrel M is mounted on a shaft 26 and carries two sets of shaper knives 27 and 28. In Figure 1 the shape of each knife 27 is illustrated, while the shapes of the knives 28 are illustrated in dotted lines. The knives 27 are for forming the relative plane-like front face of a propeller blade, while the knives 28 are for forming the back of the blade with an air-foil contour.

For rotating the mandrel M I provide a prime mover such as an electric motor 29 having a pulley 30. The pulley 30 is operatively connected by a belt 31 to a driven pulley 32 on the shaft 26. The shaft 26 is mounted in bearings 33 carried by a sub-frame 34. The sub-frame 34 is pivoted as by a pin 35 to the frame F. A pair of stop screws 36 are provided which normally contact with stop arms 37 of the sub-frame 34, such normal contact being provided by springs 38.

The springs 38 are mounted on rods 39 having their lower ends anchored in the frame F and which extend upwardly through perforations in the stop arms 37 and terminate in heads 40. The springs 38 are interposed between the heads 40 and the stop arms 37. The stop screws 36, of course, are adjustable so that the height of the knives 27 and 28 relative to the carriage C may be varied as desired.

Manual means is provided for imparting pivotal movement to the sub-frame 34 against the bias of the springs 38 comprising a crank 41 for rotating a cam 42. When the crank 41 is swung clockwise, the lobe of the cam 42 will engage the sub-frame 34 and raise it. Upon release of the crank, the springs 38 will return the sub-frame to its initial position.

55 The carriage C comprises a plate 43 having at its sides guide beads 44. The guide beads 44 travel in guideways 45 in the sides of the frame F.

For manually imparting longitudinal movement to the carriage C relative to the frame F, I pro-

vide a crank 46 for rotating a pinion 47. The pinion 47 coacts with rack teeth 48 on the bottom of the carriage C. At the forward end of the rack teeth a stop projection 49 is provided for limiting return movement of the carriage.

For automatically moving the carriage C I provide at its forward end a pair of ears 50. Cables 51 are connected with the ears 50 and are adaptable for winding on a drum 53. The drum 53 is 10 loosely journalled on a shaft 54, but may be operatively connected therewith by a jaw clutch 55. The clutch 55 may be slid along the shaft 54 (relative to which it is slidale and nonrotatable) by a yoke 56. The yoke 56 is pivoted at 57 to a 15 bracket 58 extending from the frame F.

A rod 59 is connected with an arm 60 of the yoke 56 for manually engaging the clutch 55. The rod 59 extends through a slot 61 of the frame F and to a bearing box 62 relative to which it is 20 slidably mounted. The rod then terminates in an upwardly extending handle portion 63 which may be moved toward the right for engaging the clutch 55.

The shaft 54, and thereby the clutch 55, is 25 driven from the motor 29 by a belt 64 extending around the shaft of the motor and around an enlarged pulley 65 mounted on the shaft 54. Obviously when the motor 29 is rotating and the clutch 55 is engaged, the cables 51 will be wound 30 on the drum 53, for thus automatically advancing the carriage C.

When the forward end of the carriage engages an extension 66 of the yoke 56, it will move the jaw clutch 55 to the disengaged position shown 35 in Figure 1, thus automatically preventing any excessive movement of the carriage and consequently breakage of the cables 51 or other parts of the machine.

The carriage C also carries a pair of cams 37 40 to engage the stop arms 37 and thereby automatically raise the sub-frame 34 to disengage the knives 27 and 28 from the propeller blank as the carriage approaches its forward limit of movement, as will hereinafter appear.

45 On the carriage C I illustrate a pair of propeller blanks P and P'. These may be securely clamped in position by a clamp bar 67 across their hub portions, toothed jaws 68 at the forward ends of the propeller blanks and adjustable 50 clamp jaws 69 at their rear ends. The clamp bar 67 is clamped in position by wing nuts 70 mounted on threaded rods 71 extending from the plate 43. The clamp jaws 69 are slidably mounted in housings 72 extending upwardly from the 55 plate 43 and having hubs 73.

Wing set screws 14 are threaded in the hubs 73 for urging the clamp jaws 69 toward the propeller blanks P and P' and forcing the forward ends of the blanks against the toothed jaws 68.

60 *Practical operation*

In the operation of my propeller shaping machine, a blank of rectangular cross section, as shown by dotted lines in Figures 7 or 17, for instance, is preferably cut to the shape illustrated in Figure 1, that is with its ends or the tips of the blades narrower than its central or hub portion. The propeller blank P is first laid flat on the plate 43, as shown in Figures 1 and 3, whereupon the carriage C is advanced either by the crank 46 70 or the cables 51, while the mandrel M is rotating in the direction of the arrow in Figure 2.

The knives 27 will progressively cut away the upper face of the blank P as shown in Figures 7 to 11 inclusive, the shape in Figure 7 being at

the tip of the blade and the shape in Figure 11 being adjacent the hub of the propeller blank. The blank will then appear as in Figure 3.

The angle of the cutting edge of the knife 27 relative to the axis of rotation of the mandrel M 5 determines the pitch of the blade on its front or flat side.

After one end of the blank P has been cut by the knives 27, the clamps 67 and 69 are loosened and the blank reversed end for end, whereupon the other end may be formed as shown in Figures 7 to 11, and the blank will then appear as in Figure 4. The blank is then turned over and placed in the position of the blank P' in Figure 1. So that it will be thinner at the tip than at the hub, as illustrated in Figures 12 to 16, and to avoid having it produce thick edges at the tip of the blade as shown in Figure 7, I arrange a filler block 75 on the plate 43 for the forward end of the propeller blank (see Figure 5), or the top 20 of the plate 43 may be formed in this shape.

After the operation shown in Figure 5 has been completed, the blank is turned end for end to produce the finished propeller, as shown in Figure 6, the hub portion thereof being indicated by the 25 bracket 76 and the blade portions by the brackets 17.

Shaping the propeller blank by the machine as thus described, produces a propeller of the desired cross sectional shape from hub to tip as 30 illustrated in Figures 12 to 16, but one which does not have a helical pitch.

It is possible, however, to give helical pitch to the propeller by the mere expedient of progressively inclining the carriage laterally as it moves 35 along the frame F. This is accomplished by the construction shown in Figures 22 and 23, wherein a pair of carriages are provided for the blanks P and P', one comprising a plate 43' and the other a plate 43''. The guideways for these plates are 40 indicated at 45° for the plate 43' and 45'' and 45''' and for the plate 43''.

Figure 23 illustrates how one of the guideways for the plate 43'' is level and the other is formed in two sections, each of which is inclined so that 45 its forward end drops relative to the rear end thereof. This progressively inclines the carriage laterally from the position almost level across at the end to a position somewhat like that shown for the plate 43''' in Figure 22, near the hub. 50 These plates have pairs of rollers 78 at the positions indicated at the arrows 22 and 22a in Figure 2, and which roll along the guideways 45'' and 45''''. This progressively inclines the blank laterally as indicated by dotted lines in Figures 17 55 to 21, level position being indicated by the line L which is at a predetermined position from the axis of rotation of the mandrel M.

It will be noted that the inclination of the blade shown in section in Figures 17 to 21 varies so 60 that its pitch is less in Figure 17 at the tip of the blade than in Figure 21 adjacent the hub thereof. The variation in depth of the cut of the knives 28 effectively shapes the propeller blade down to a thin cross section at the tip and 65 a thick one at the hub, yet preserves the airfoil contour of the back of the blade throughout, as is obvious from an inspection of Figures 12 to 21.

The cross sectional shape and pitch of the 70 blades are automatically secured with my machine, it being merely necessary to clamp the blanks in position with such spacers as may be needed and feed them to the knives 27 and 28.

In the modified form of my machine as shown 75

particularly in Figures 22, 24 and 25, a means is illustrated of cutting a taper on the blade and also tilting the blade laterally to cut a helix. To accomplish this there is provided on the carriage 43' a clamp 67' and on the carriage 43'' a clamp 67'' so that the blanks P and P' respectively may be separately clamped to their respective carriages by means of a combined bolt and wing nut 70' at the end of each clamp. The blank P travels in a straight undeviating path underneath the cutters 27 as described in connection with the preferred form of my device, except that when desired a tapered wedge may be placed beneath the blank in order to lift the right hand end slightly so that the longitudinal axis is tilted. In a similar manner the blank P' is secured upon the carriage 43'' in a tilted position longitudinally by use of a tapered spacer 75'. The tapered spacer is thicker at the right hand end as viewed in Figure 25 than at the left so that the blank P' will be tilted higher at the right end than at the left. Since the right end will be closer to the rotating mandrels 28 than the portion near the hub more material will be cut from the end, thereby producing a thinner section at the tip than at the hub. The motion of the carriage in a direction from left to right covers only a distance of half the length of the blank so that one side only is cut at a time.

At the same time a taper is being cut on the blank the carriage is likewise being inclined laterally. Since the guideway 45''' is horizontal the roller 78 which lies within it will cause the right hand side of the carriage 43'' as viewed in Figure 22 to travel in a horizontal plane. At the same time the rollers 78 which lie respectively one in each of the inclined guideways 45'' will gradually raise the left hand side of the carriage 43'', as viewed in Figure 22, as the carriage passes from left to right as viewed in Figure 25.

The two guideways 45'' have precisely the same alignment and are provided in duplicate so that the rollers 78, one at each end of the carriage, will be raised simultaneously by equal amounts. At the start of movement of the carriage from the position shown in Figure 25, the blank P' will have a pronounced lateral tilt somewhat as shown in Figure 22. At the same time the right hand end will be closer to the mandrel 28 because of the tapered spacer 75' and the mandrel will cut the blank to the shape shown in Figure 17.

As the carriage 43'' passes from left to right the rollers 78 will gradually climb upward in the guideways 45'', thereby progressively lessening the lateral tilt as shown in Figures 18, 19 and 20. At the same time, however, the tapered spacer 75' will be gradually lowering the position of the blank relative to the mandrel 28 so that a lesser quantity of material will be cut from the adjacent side of the blank until the blank portion near the hub will be shaped to a form somewhat like that shown in Figure 21.

It will thus be apparent that the blank of the propeller blade can be tapered as to thickness from a rather thin dimension at the tip to a rather thick dimension at the hub at the same time as a variable contour is cut upon the rear side of it.

In operation, the first blank is cut on both ends by the knives 27 and then transferred to the

position of the blank P', and a second blank placed in the position of the blank P. Thereafter as the carriage C is advanced, two blanks may be worked on at the same time, the front of one being shaped by the knives 27 and the back of the other being simultaneously shaped by the knives 28. It is accordingly possible to quickly shape the blades of the propeller blank after it has once been cut to its desired contour.

With a machine of the character disclosed, the production of propeller blades of the proper pitch and cross sectional shape is facilitated to a degree making it possible for one man to turn out a considerable volume of perfectly shaped blades in a day's time.

Some changes may be made in the construction and arrangement of the parts of my device without departing from the real spirit and purpose of my invention, and it is my intention to cover by my claims any modified forms of structure or use of mechanical equivalents, which may be reasonably included within their scope.

I claim as my invention:

1. In a propeller shaping machine, a frame, means for supporting a pair of propeller blanks thereon for longitudinal movement, a shaft, a pair of jointly operable shaping elements for the propeller blanks spaced on opposite sides of the center of said shaft, one being shaped for forming the front of one of the blanks and the other being shaped for simultaneously forming the back of the other blank with an air-foil contour, means on the frame for inclining one of said propeller blanks laterally during its longitudinal movement to thereby change the pitch of said propeller blade from tip to hub of the propeller blank.

2. In a propeller shaping machine, a frame, a carriage movable relative thereto, means for clamping a pair of propeller blanks on said carriage, a mandrel rotatable in fixed position having a knife for shaping the front of one of said propeller blanks and a knife for simultaneously shaping the back of the other propeller blank with an air-foil contour, and means engaged by said carriage at one limit of its movement to disengage both said knives from said propeller blanks adjacent the hub portions thereof.

3. In a propeller shaping machine, a frame, a carriage mounted on said frame for movement in a straight line within a horizontal plane, means including a tapered spacer beneath a propeller blank for clamping said propeller blank immovably relative to said carriage in a position such that the longitudinal axis of said propeller blank is inclined relative to the line of travel of the carriage, a rotary mandrel in the line of travel of the propeller blank having a knife for shaping the contour of said propeller blank, means for moving said carriage and blank in a straight line perpendicular to the axis of said rotary mandrel so that the blank is in contact with the mandrel for progressively cutting a longitudinal taper on the blade of the propeller, and coacting guide means on said frame and said carriage respectively, one of which is inclined in the direction of travel of the carriage for progressively tilting said carriage laterally during its travel to progressively rotate the blade about its longitudinal axis and change the pitch of the propeller blade being shaped.

WILLIAM G. DUNN.
